UNITED STATES PATENT OFFICE

ROBERT E. BRAGG, OF WASHINGTON, DISTRICT OF COLUMBIA

DESIGN FOR A SOUVENIR EMBLEM OR SIMILAR ARTICLE

Application filed November 16, 1931. Serial No. 41,748. Term of patent 14 years.

To all whom it may concern:

Be it known that I, ROBERT E. BRAGG, a citizen of the United States, residing in Washington, District of Columbia, have invented a new, original, and ornamental Design for a Souvenir Emblem or Similar Article, of which the following is a specification, reference being had to the accompanying drawings, forming part thereof.

Fig. 1 is a plan view of a souvenir emblem or similar article showing my design, and

Fig. 2 is an edge view thereof looking upward from the bottom end.

I claim:

The ornamental design for a souvenir emblem or similar article as shown.

ROBERT E. BRAGG.
